UNITED STATES PATENT OFFICE.

WALTER R. LAINE, OF LOS ANGELES, CALIFORNIA.

BLADE-PROTECTING KNIFE.

1,024,086.

Specification of Letters Patent.

Patented Apr. 23, 1912.

Application filed April 7, 1911. Serial No. 619,526.

To all whom it may concern:

Be it known that I, WALTER R. LAINE, a citizen of the United States, residing in the city of Los Angeles, State of California, 5 have invented a new and useful Blade-Protecting Knife, of which the following is a specification.

An object of this invention is to provide an improved blade-protecting attachment, 10 applicable to knives differing considerably in design, but more particularly adapted for use on knives having double-edged blades of the non-foldable type. This attachment is adapted to protect the hands of the user and 15 also, when the knife is being sharpened, to guard against the edge of the blade being brought into contact with the sharpening instrument or surface in an improper manner.

20 Another object of this invention is to provide an improved photographer's etching tool the blade of which is capable of being adjustably set in a variety of positions with relation to the handles.

25 Referring to the accompanying drawings, which illustrate the invention, Figure 1 is a side elevation of the knife showing the blade-protecting members in the extended, or operative, position, one of the side plates 30 being broken away to show interior parts more clearly; Fig. 2 is a side elevation of the reverse side of the knife showing the blade-protecting members in the retracted, or inoperative position and also showing the 35 blade adjusted at a different angle; Fig. 3 is a longitudinal mid-section on line x^3 of Fig. 1; Fig. 4 is an enlarged cross-section, the line of section being indicated on Fig. 1 by line x^4 ; Fig. 5 is a side elevation of a 40 blade adapted for use in said knife; Fig. 6 is a perspective view illustrating the use of the blade-protecting arms in sharpening a double-edged blade.

45 Referring in detail to the drawings, the handle may consist of side plates 1 between which is clamped a spring member 2 by means of two or more rivets 3. Said member 2 has resilient limbs 4 which operate upon the blade-protecting arms 5. Said 50 blade-protecting arms 5 are pivoted one near each edge of the handle, by means of rivets, or pins 6 which also aid in holding together the side plates 1. Said arms 5 are desirably square in cross-section near the pivots 6 and 55 provided with right angles upon which the spring limbs 4 act in the usual manner of

operating blades of pocket knives to hold said arms yieldingly in the extended position, shown in Fig. 1, or in the retracted position, shown in Fig. 2.

60 As shown in Fig. 4, the arms 5 are each provided with a round portion upon which is mounted a sleeve 7. Said sleeves are rotatable upon said arms and are kept in place by a tip 9 on each arm.

65 As shown in the first three views, at the left end of the handle side plates 1 are provided with narrowed end portions 11 which are brought together as seen in Fig. 3 to hold a blade 12 by means of a screw 13 and 70 nut 14. Said blade 12 (see Fig. 5) has a shank 15 furnished with an open slot 16 whereby the shank of the blade may be made to pass astride the retaining screw 13. By 75 loosening the nut 14 (or screw 13) the blade 12 may be adjusted to various angles as indicated in Fig. 2. The head of screw 13 may be soldered to the side plate extension 11 at that side of the knife and the adjustment effected by the nut 14 only. A variety of 80 blades may be employed if they are all provided with similar shanks.

85 In Fig. 6 is illustrated the use of the blade-protecting arm in sharpening a double-edged blade. In thus using the knife the arm rests upon the strop and the blade and handle are moved in the same manner as in sharpening an ordinary razor. The sleeve 7 protects the other edge of the blade from cutting the strop 19. Said sleeve also rotates and lessens friction. In order to perform the function of protecting the edges of the blade during sharpening, it is necessary that these blade protecting arms be located close to, parallel with, and in substantially the same plane with the blade of 90 the knife.

95 The side plates are recessed at 21 to permit the fingers to grasp the arms 5 to extend the latter.

100 The herein described knife is well suited to the use of photographers for an etching tool. The blade being comparatively thin and sharpened at both edges, there is nothing to obscure the vision of the operator 105 from the surface upon which he is operating.

I claim:

110 1. In a knife, a handle consisting of a member having resilient limbs and a pair of side plates covering said limbs, said plates having side portions extending laterally beyond said limbs, a double-edged blade

attached to one end of said handle, and a pair of blade-protecting arms pivoted to and between the edge portions of said plates, each of said arms having a heel portion in engagement with one of said resilient limbs to hold said arm yieldingly in a blade-protecting position or in a completely retracted position.

2. In a knife, a pair of side plates, an elongated spring member having a solid portion secured between one end of said side plates and a pair of spring limbs projecting toward the other end of said side plates, said side plates extending laterally beyond said limbs, a blade attached to the end of the knife toward which said limbs extend, and a pair of pivoted blade-protecting arms, said arms having heel portions upon which said limbs operate to hold said arms yieldingly extended along the edges of the blade

to protect the same, or oppositely extended in the folded position between said side plates.

3. In a knife, a handle, a blade, means to secure said blade to one end of said handle, a protecting arm carried by said handle and adapted to swing into position parallel to said blade to protect an edge thereof, and a rotatable sleeve carried by said arm, said sleeve being adapted to operate as an anti-friction device in sharpening the knife.

In testimony whereof I have hereunto signed my name in the presence of two subscribing witnesses at Los Angeles, in the county of Los Angeles and State of California, this 29th day of March 1911.

WALTER R. LAINE.
